UNITED STATES PATENT OFFICE.

DUDLEY R. MORRISON, OF HARTFORD CITY, INDIANA.

VAPORIZER FOR OIL-ENGINES.

SPECIFICATION forming part of Letters Patent No. 771,881, dated October 11, 1904.

Application filed January 25, 1904. Serial No. 190,516. (No model.)

To all whom it may concern:

Be it known that I, DUDLEY R. MORRISON, a citizen of the United States, residing at Hartford City, in the county of Blackford and State of Indiana, have invented certain new and useful Improvements in Vaporizers for Oil-Engines, of which the following is a specification.

The object of this invention is to utilize crude petroleum as the source from which a supply of hydrocarbon is obtained for operating an explosive-engine, to provide means for vaporizing the oil, and then to explode the vapor without the aid of an electric spark, heated tube, or other means than that provided by the heat generated in the cylinder from the previous explosion.

I accomplish the objects of the invention by the mechanism illustrated in the accompanying drawings, in which—

Figure 1 is a vertical longitudinal section of an engine embodying my improvements, and Fig. 2 a transverse section on the line 2 2 of Fig. 1.

Like characters of reference indicate like parts throughout both views of the drawings.

3 is the engine-cylinder; 4, the engine-shaft; 5, the crank-wheel; 6, the piston, which is connected by pitman 7 with a wrist-pin on the

30 crank-wheel.

8 is an air-tight housing which surrounds the crank-wheel.

The cylinder 3 has only one head 9, the inner end being open into the housing 8. 10 is an air-inlet to the interior of the said housing and is controlled by a suitable spring-closed valve which permits of an inflow of air, but not of a discharge of air therethrough. The cylinder is surrounded with the usual water-jacket 11.

12 is a port which allows the air in the housing 8 to enter the cylinder within the area of travel of the piston, so as to be uncovered when the piston is at the inner end of its stroke or nearest to the crank-wheel, and 13 is the exhaust-port, which is somewhat farther out from the crank-wheel than port 12.

Inside of the cylinder, near the head 9, is a wall 14, which provides a chamber 15 for heating the hydrocarbon vapors. Extending into

the cylinder from the wall 14 is the series of flanges 16, which extend diagonally across the said wall in alternate opposite directions, the lower end of the first discharging upon the higher end of the next below, and so on. 55 These flanges are to receive a discharge of the hydrocarbon (crude oil) through pipe 17, beginning at the top one. Their outer edges are elevated, so as to form a trough for the oil to run in. The pipe 17 communicates 60 with the can or reservoir 18. It is provided with the cock 19 and the check-valve 20, the latter being for the purpose of preventing back pressure to the reservoir when an explosion occurs. At the lower side of the cylinder, under the chamber 15, is the sleeve 21, having hollow walls that are connected with the reservoir 18 by pipe 22.

23 is a pipe leading from the hollow wall of the sleeve to the vertical nozzle 24, at the 70 lower end of which is the pan 25. The latter is filled with oil by overflow from the nozzle as the first step in starting the engine. This oil is ignited, the heat passing up through the sleeve and through the chamber 15 and out 75 through the flue 26. The latter has a cover 27, by which the flue is closed when desired. The chamber 15 is at the sides, as well as at the back, of wall 14 and quickly heats the latter, so that oil discharged upon the flanges 16 80 will be vaporized. When this condition obtains, the cover 27 is closed and the oil-supply through pipe 23 is cut off by means of cock 28 and the upper supply relied on to run the engine. The head 9 is lined with asbestos 85 29 to prevent the radiation of heat through said head.

The operation of my improved engine is as follows: Starting with the piston in the position shown in Fig. 1, the latter is moved by 90 hand toward the crank-wheel to the end of the stroke, which opens the exhaust-port and after that the air-supply port, and the compression of air in the housing forces air into the cylinder to mix with the hydrocarbon 95 vapor which has been generated from the oil by the means described in the foregoing paragraph. Then the piston is made to travel back, so as to close both ports and compress the mixture of air and hydrocarbon vapor in 100

the outer end of the cylinder, and when the pressure reaches a certain maximum spontaneous combustion will ensue, the force of which will drive the piston back toward the 5 crank-wheel. The continued generation of the hydrocarbon vapor by the heat generated at each explosion and the alternate filling of the cylinder with air and the compression of the air and vapor will keep the piston continuously reciprocating in the cylinder.

Having thus fully described my invention, what I claim as new, and wish to secure by Letters Patent, is—

1. In an explosive-engine, a cylinder having 15 one closed end, a partition adjacent to said closed end forming a heating-chamber, diagonal flanges in alternate opposite directions on said partition forming oil-runs, an oil-supply to said runs, an air-supply to the cylinder 20 and means for compressing the air and vapor to spontaneous combustion.

2. In an explosive-engine, a cylinder having an end heating-chamber, means for heating said heating-chamber to start the engine, oil- 25 runs extending into the cylinder from the inner wall of said chamber, means for supplying oil to said oil-runs, means for supplying air to the cylinder, and a piston to compress the air and hydrocarbon vapor.

3. In an explosive-engine, a cylinder having 30 an end heating-chamber open to atmosphere at the bottom and having a valve - closed top opening, a sleeve at the bottom opening having hollow walls, an oil-cup below said sleeve, an oil-supply to the chamber in the walls of 35 the sleeve and an oil-supply from said chamber in the sleeve having an overflow into said cup, means for stopping the supply of oil to the sleeve and for closing the opening to atmosphere at the top of the said heating-chamber, oil-runs supported by the inner wall of said

heating-chamber and opening into said cylinder, an oil-supply thereto, an air-supply to the cylinder and a piston reciprocating in said cylinder to compress the air and vapors for the 45 purposes specified.

4. In an explosive-engine, a cylinder having an end heating-chamber lined with asbestos or other good non-conductor of heat on its outer surface, oil-runs supported by the inner 50 wall of said heating-chamber opening into said cylinder, an oil-supply thereto, an air-supply to the cylinder and a piston reciprocating in said cylinder to compress the air and vapors for the purposes specified.

5. In an explosive-engine, a cylinder having an end heating-chamber, oil-runs supported by the inner wall of said heating-chamber opening into said cylinder, an oil-supply thereto, an air-supply to the cylinder, a piston reciprocating in said cylinder to compress the air and vapors and fire it with the aid of the heat of former explosions in the cylinder and a water-jacket surrounding the cylinder but not the heating-chamber.

6. In an explosive-engine, a cylinder having an end heating-chamber, oil-runs opening into said cylinder and supported by the inner wall of said heating-chamber, an oil-supply thereto, an air-supply to said cylinder, an exhaust 70 between said air supply and said heating-chamber, and a piston reciprocating in said cylinder to open and close the air-supply and exhaust ports and to compress the air and hydrocarbon vapors.

In witness whereof I have hereunto set my hand and seal, at Indianapolis, Indiana, this 9th day of January, A. D. 1904.

DUDLEY R. MORRISON. [L.S.]
